UNITED STATES PATENT OFFICE.

CLARENCE H. FORNEY, OF JERSEY CITY, NEW JERSEY.

SPOOL.

1,159,204.

Specification of Letters Patent.

Patented Nov. 2, 1915.

Application filed April 27, 1915. Serial No. 24,218.

To all whom it may concern:

Be it known that I, CLARENCE H. FORNEY, a citizen of the United States, and a resident of Jersey City, in the county of Hudson and State of New Jersey, have invented a new and Improved Spool, of which the following is a full, clear, and exact description.

This invention relates to spools and has for an object the provision of an improved spool structure which is comparatively cheap to manufacture and yet amply strong for answering all purposes for which it is intended.

Another object of the invention is to form a spool from tubular members and a plurality of bracing members arranged therein for holding the tubular members in the form or shape of the conventional spool.

A still further object of the invention is to provide a substitute for the conventional solid wooden spool by forming a spool from a plurality of built-up parts.

In the accompanying drawings: Figure 1 is a longitudinal vertical section through a spool embodying the invention, the same being taken approximately on line 1—1 of Fig. 2; Fig. 2 is a transverse horizontal section through Fig. 1 on line 2—2; Fig. 3 is a top plan view, edge view and side view of one of the bracing members shown in Fig. 1; Fig. 4 is a view similar to Fig. 2 except that a slight modified form of the invention is disclosed.

Referring to the accompanying drawings by numerals, 1 indicates a tubular case or body of any desired material, as for instance pasteboard, and 2 and 3 indicate frusto-cones. In order to hold the frusto-cones 2 and 3 in place, as well as the tubular center or body 1, a plurality of bracing or retaining members 4 are provided. In Figs. 1 and 2 four bracing members are provided, though more or less may be used as desired, as for instance, three may be used as shown in Fig. 4. These bracing or retaining members are shown in detail in Fig. 3, wherein it will be observed that a body 5 is provided and heads 6 and 7. The heads 6 and 7 are each provided with beveled or inclined surfaces 8 on the outside and a camming surface 9 on the inside. A plug 10, preferably of wood, is arranged at each end of the spool, as shown in Fig. 1, and presses against the cam faces 9 so as to spread the members 4 and cause the same to press against the frusto-cones 2 and 3 and also against the

tubular body 1. End members 11 and 12 are provided which fit the ends of the cones or plugs 10 and also fit the interior of the frusto-cones 2 and 3.

In assembling the parts of the spool, adhesive is applied to the interior surface of each of the bracing members 4 and to all of the cam faces 9. In addition, if desired, adhesive could be supplied to the members 1, 2 and 3 as well as to the cones 10, though usually this is not necessary. After the adhesive has been placed in position the bracing members 4 are threaded through tubular member 1 and also through the frusto-cones 2 and 3, after which the cones 10 are forced into position, these cones carrying the end members 11 and 12 which, if desired, may be secured thereto by an adhesive. After the parts have been properly assembled the cones 10 are bored and the spool properly trued in any suitable manner.

The parts 1, 2 and 3 are preferably made from paper or some good quality cardboard, though other material may be used if desired, as for instance, wood or fiber. The bracing or reinforcing members 4 are preferably formed from wood, while the cones 10 are also preferably formed from wood, so as to make a comparatively light spool while presenting a strong spool.

What I claim is:—

1. A built-up spool comprising a tubular body or center, frusto-conical ends, a plurality of identically constructed bracing members arranged within said tubular member and said ends, each of said bracing members pressing against said tubular member and against said ends and a spreading member for spreading said bracing members and forcing the same radially outwardly against said body and said ends.

2. A spool comprising separate ends and a separate body or central portion, a plurality of bracing and reinforcing members arranged interiorly of said ends and said central portion, and means arranged adjacent the ends of the spool for pressing said reinforcing members against said ends and said central portion.

3. A built-up spool comprising a tubular center, a pair of hollow ends, a plurality of bracing members fitting in said body and said ends, said bracing members having cam faces at each end, and a cone arranged at each end of the spool and engaging said cam faces for spreading said bracing mem-

bers and pressing the same against said ends and said tubular body.

4. A spool comprising a tubular body of paper, a pair of frusto-conical ends of paper formed hollow, a plurality of reinforcing members of comparatively light material, said reinforcing members being formed exteriorly so as to fit said ends and said body and formed interiorly with cam faces, and 10 a cam member arranged adjacent each end of the spool and adapted to engage the cam faces for holding said reinforcing members against said body and said ends.

5. A spool of the character described, comprising an outer shell or casing of material having the characteristic of paper, a plurality of identically constructed bracing members arranged in the casing, said bracing members being formed of material having substantially the characteristic of wood, and a wedging member arranged adjacent each end of the spool for holding the bracing members against the casing.

6. In a spool of the character described, a 25 casing formed substantially of the same shape as the conventional spool, said casing being formed of thin material, a plurality

of bracing members formed of wood arranged in the casing and fitting the same, each of said bracing members being provided with a cam or beveled face, and a wood cone fitting against said beveled or cam faces for holding the bracing members against said casing.

7. In a spool of the character described, 30 a comparatively thin casing formed in the same shape as the conventional spool, a pair of end covering disks fitting on the ends of said casing, a plurality of bracing members arranged in the casing and extending from one end to the other, said bracing members being formed on the exterior with a contour fitting the casing and on the interior with an inclined or beveled face at each end, and a cone of wood fitting said inclined or beveled face at each end of the spool.

In testimony whereof I have signed my name to this specification in the presence of two subscribing witnesses.

CLARENCE H. FORNEY.
